CIRCUITS FOR ELECTRON DISCHARGE
DEVICES

Maurice Masnou, Paris, France, assignor to General Electric Company, a corporation of New York

Application October 29, 1924, Serial No. 746,561
In France November 3, 1923

10 Claims. (Cl. 179—171)

My present invention relates to circuit arrangements for use with electron discharge devices, particularly thermionic tubes of the three-electrode type.

It is well known that the plate current of a three-electrode thermionic tube is affected by variations in the current supplied for heating the usual filamentary cathode, for example, a telephone inserted in the plate circuit will give a sound whose pitch is a function of frequency of variations of the heating current. If a resistance is placed in shunt to the filament terminals and the plate circuit is brought to a point in this resistance having the same potential as the central point of the filament the noise in the telephone will decrease in intensity. If the grid potential is made negative the noise will be still further decreased, but when several tubes are coupled together by transformers or resistance couplings, the noise produced in the output circuit of the last tube will still be very objectionable.

The object of my invention is to provide circuit arrangements whereby the cathodes of three-electrode thermionic tubes may be supplied with variable heating current, such, for example, as a low frequency alternating current, and the effect of the variations in the heating current upon the output circuit of the last tube of a series will be eliminated to such an extent that it will be unobjectionable.

The novel features which I believe to be characteristic of my invention are set forth with particularity in the appended claims, my invention itself, however, both as to its organization and method of operation will best be understood by reference to the following description taken in connection with the accompanying drawings in which Fig. 1 shows diagrammatically a circuit arrangement in which my invention is applied to a system for amplifying radio frequency currents; Fig. 2 shows the application of my invention to the detection of high frequency currents; Fig. 3 shows its application to the amplification of audio frequency currents; and Fig. 4 shows a circuit arrangement in which all three of the functions of Figs. 1, 2 and 3 are combined in one circuit organization.

In the arrangement of Fig. 1, I have indicated two tubes 1 and 2, the cathodes of which are heated by means of alternating currents supplied by the transformers 3 and 4. The grid and plate returns are brought to intermediate points in the resistances 5 and 6, which are shunted across the transformer secondaries. The plate circuit of device 1 includes the usual battery 7, resistance 8 and primary 9 of the transformer 10. The resist-

ance 8 is connected in series with the secondary 11 of transformer 10 and in the grid circuit of device 2. The plate circuit of tube 2 includes a battery 12 and primary 13 of an output transformer. The signals to be amplified are impressed upon the grid circuit of tube 1 by means of an input transformer 14. The grid of tube 1 is preferably made negative by means of a biasing battery 15. When the heating currents of the two tubes increase the plate currents tend to increase. An increase in plate current in tube 1 tends to make the grid of tube 2 more negative and this counteracts the tendency of the plate current of tube 2 to increase. The primary and secondary windings 9 and 11 of transformer 10 are connected in such a way that the signaling potentials impressed upon the grid of tube 2 through the transformer reinforce the signal potential impressed upon the grid of tube 2 by means of resistance 8. I have found that with the arrangement described amplified radio frequency current supplied to the output of transformer 13 is as free from fluctuations due to the heating current as would be the case if the cathodes of the tubes had been heated by direct current.

In the arrangement shown in Fig. 2, tube 1 is made to serve as a detector by inserting the usual grid condenser 16 and grid leak 17 in the grid circuit. In this case the grid of tube 1 is preferably made positive by means of the biasing battery 18. The plate circuit of tube 1 includes the primary winding 19 of an audio frequency transformer and a choke 20, whose impedance is substantially negligible for currents of the frequency employed for heating the cathodes. The voltage variations at the terminals of choke 20 are supplied to the grid of tube 2 through a condenser 21. A discharge resistance 22 in the grid circuit to tube 2 insures a suitable mean potential for the grid of that device. A resistance 23 is also preferably included in the plate circuit of tube 2, although this may be omitted if desired. It will be observed that with the connections shown the plate currents of tubes 1 and 2 flow in opposite directions through the primary 19 of the audio frequency transformer 24.

The operation of this system is as follows:—

The circuits are so adjusted that when no signals are being received the plate current variations in the two tubes are equal, and since the two currents flow in opposite directions through the primary 19 of transformer 24 no effect will be produced in the output circuit. When, however, a signal is received a potential variation is produced across the choke 20, which is applied

through the condenser 21 to the tube 2. This causes the current through tube 2 to vary in the opposite direction to the variation of current in tube 1, and thus the changes in the signaling currents of the two tubes flowing through primary 19 of the audio frequency transformer 24 reinforce each other.

In the arrangement shown in Fig. 3, which is adapted for the amplification of audio frequency currents, the telephone receiver 25 is inserted in the two plate circuits in such a way that the two plate currents flow through the telephone receiver in opposite directions. The action of the circuit in eliminating the effect of variations in the heating current and the reinforcing of the signaling currents produced in the two plate circuits are similar in this case to that occurring in Fig. 2. The grid of the device is in this case preferably made negative by the biasing battery 26. If desired, a resistance may be inserted in the plate circuit of device 2, as in the arrangement of Fig. 2, and the telephone receiver 25 may be connected to the plate circuits by means of a transformer.

In the arrangement of Fig. 4 I have shown a six-tube outfit adapted for the amplification and detection of radio signals received upon an antenna 27. Heating current for the filament of all of the tubes may be supplied by transformer 28, having a single primary winding 29 and individual secondary windings 30 to 35 inclusive. If desired, independent transformers may be used. A transformer having considerable leakage flux is also advantageous. Tubes 36 and 37 act as radio amplifiers and are connected by means of the high frequency transformer 38 to the grid circuit of the tube 39, which acts as a detector. Tube 39 in conjunction with tube 40 also serves as an audio frequency amplifier as in the arrangement shown in Fig. 2, and tubes 41 and 42 act as a low frequency amplifier in the manner described in connection with Fig. 3. Batteries 43, 44 serve to supply plate currents to the three pairs of tubes.

It will of course be understood that the circuit arrangements described may equally well be used where the plate circuits of the tubes are supplied by suitably rectified alternating current.

While I have shown and described certain applications of my invention, it will be obvious that many modifications in the manner in which it is applied may be made without departing from the scope thereof as set forth in the appended claims.

What I claim as new and desire to secure by Letters Patent of the United States is:—

1. A circuit arrangement for three-electrode thermionic tubes comprising a pair of cascade connected tubes having plate and grid circuits, means for supplying variable currents for heating the cathodes of said tubes, and means common to a circuit of each tube whereby variations in the plate current of one tube produced by reason of variations in the heating current are compensated by the variations in the plate current of the other tube.

2. A circuit arrangement for three-electrode thermionic tubes comprising a pair of tubes having plate and grid circuits, means for supplying variable currents for heating the cathodes of said tubes, said tubes being connected in cascade for successive amplification, means common to a circuit of each tube whereby variations in the plate current of one tube produced by variations in the heating current are compensated by the

variations in the plate current of the other tube and additional means whereby variations in a signaling current in one tube produce amplified variations in signaling current in the other tube.

3. A circuit arrangement for three-electrode thermionic tubes comprising a pair of cascade connected tubes having plate and grid circuits, means for supplying low frequency alternating currents for heating the cathodes of said tubes, means common to a plate circuit of each tube whereby variations in the plate current of one tube produced by reason of variations in the heating current are compensated by the variations in the plate current of the other tube and high frequency coupling means connected in circuit with said last means whereby high frequency variations are supplied from one tube to the other.

4. A circuit arrangement for three-electrode thermionic tubes comprising a pair of tubes having plate and grid circuits, means for supplying low frequency alternating currents for heating the cathodes of said tubes, said tubes being connected in cascade for successive amplification, means common to the plate circuit of one tube and the grid circuit of the other tube whereby variations in the plate current of one tube produced by variations in the heating current are compensated by the variations in the plate current of the other tube, additional means connected in circuit with said last means whereby variations in a signaling current in one tube produce amplified variations in signaling current in the other tube.

5. A circuit arrangement for three-electrode thermionic tubes comprising a pair of tubes having plate and grid circuits, means for supplying variable currents for heating the cathodes of said tubes, means for supplying signaling currents to the grid circuit of one tube, means for supplying amplified current variations from the plate circuit of the first tube to the grid circuit of the second tube, and a conductive connection from the plate circuit of the first tube to the grid circuit of the second tube for compensating the effect in the plate circuits of the two tubes of variations in the plate current produced by reason of variations in the heating currents.

6. A circuit arrangement for three-electrode thermionic tubes comprising a pair of tubes having plate and grid circuits, means for supplying variable currents for heating the cathodes of said tubes, means for supplying signaling currents to the grid circuit of one tube, means for supplying amplified current variations from the plate circuit of the first tube to the grid circuit of the second tube, and a conductive connection between the circuits of the two tubes for compensating the effect in the plate circuit of the second tube of variations in the plate current produced by reason of variations in the heating currents.

7. The method of reducing disturbing effects of variable energizing currents in the circuits of a cascade system of electron discharge devices, which includes applying the disturbing currents arising in a circuit of each alternate discharge device in the cascade system to a circuit of the next adjacent discharge device intermediate said alternate discharge devices in phase to neutralize the disturbing current arising in the respective next adjacent discharge device.

8. A circuit arrangement for three-electrode thermionic tubes comprising a pair of tubes having plate and grid circuits, means for supplying variable currents for heating the cathodes of said

- tubes, said tubes being connected in cascade for successive amplification, means common to a circuit of each tube whereby variations in the plate current of one tube produced by variations in the heating current act to oppose variations of plate current in the other tube and a reactive coupling between the plate circuit of the first tube and the grid of said other tube, said coupling being in circuit with said means.
- 5 9. A circuit arrangement for three-electrode thermionic tubes comprising a plurality of tubes having plate and grid circuits, means for supplying variable currents for heating the cathodes of said tubes, said tubes being connected in cascade for successive amplification, and connections whereby variations in the plate current of one tube produced by variations in the heating cur-
- 10 15

rent act on the grid of the next adjacent tube in said cascade arrangement to prevent variations in the plate current in next adjacent tube.

10. A circuit arrangement for three-electrode thermionic tubes comprising a pair of tubes having plate and grid circuits, means for supplying variable currents for heating the cathodes of said tubes, said tubes being connected in said cascade for successive amplification, and an impedance connected in the plate circuit of one tube and in the grid circuit of the other tube whereby variations in the plate circuit of one tube resulting from heating current variations in said tube and variations in the heating current of the other tube produce compensating effects on the plate current of the other tube.
